UNITED STATES PATENT OFFICE.

CHARLES E. JONES AND DONALD A. WHOOLERY, OF OUTCROP, PENNSYLVANIA.

CLOSURE FASTENER.

Application filed June 3, 1927. Serial No. 196,305.

The present invention relates to improvements in closure fasteners and has for its principal object to provide a latch construction for use more particularly on boilers for holding the swinging doors of the fire box of the boiler in a closed position.

One of the important objects of the present invention is to provide a closure fastener wherein a latch is pivotally carried by the 10 vertically swinging door, the latch being mounted on the door in such a manner as to cause the upper end of the latch to be maintained in engagement with the keeper provided therefor above the door due to the 15 weight of the latch.

A still further object of the invention is to provide a closure fastener wherein a pair of keepers are provided above and below the vertically swinging door, the latch associated 20 with the door being of such construction as to be in engagement with the respective keepers for positively securing the door closed.

A still further object of the invention is 25 to provide a closure fastener of the above mentioned character which is of such construction as to permit the same to be readily and easily attached to a boiler without necessitating any material alterations of the parts 30 of the boiler with which the present device is associated.

A still further object is to provide a closure fastener which is simple in construction, inexpensive, strong and durable and further 35 well adapted to the purpose for which it is designed.

Other objects and advantages of the invention will become apparent from the following description of the same.

40 In the accompanying drawing forming part of this application and in which like numerals indicate like parts:

Figure 1 is a fragmentary front elevation of a boiler showing a pair of cooperating vertically swinging doors associated therewith and for disclosing more clearly the manner in which the present device secures the doors in a closed position.

Figure 2 is a top plan view, and

50 Figure 3 is a vertical sectional view taken substantially on line 3—3 of Figure 1 looking in the direction of the arrows.

In the drawing wherein for the purpose of illustration is shown the preferred embodiment of our invention, the numeral 1 designates the front of a boiler, the same

being provided with a suitable opening for communication with the fire box, and this opening is normally closed by a pair of vertically swinging doors 2 and 3, respectively, the same being hingedly secured at their outer ends on front of the boiler as at 4 in the manner well known in the art. As clearly shown in Figures 1, 2 and 3 of the drawing the upper edge of each of the 65 doors is beveled and this is indicated by the numeral 5.

Our improved closure fastener comprises a pair of substantially double L-shaped latch members 6 and 7, respectively, one being 70 provided for each door, and as these latches are of the same construction, the description of one will suffice for the description of both. The latches are disposed vertically on the outer face of the doors adjacent the inner 75 opposed free edges thereof and the upper longer arm portion 8 is pivotally attached at a point intermediate its ends to the respective doors as at 9. By attaching the latches to the doors in this manner, wherein 80 the same are pivotally mounted on the doors at points adjacent the upper ends of the latches, the lower major portions of the latches will act as a weight, and this will be readily obvious from the construction 85 shown in Figure 1.

The upper end portion of the longer arm 8 is slightly bent inwardly for disposition above the beveled portion 5 of each door as indicated at 10 and a suitable guide bracket 90 11 is secured on the beveled portion of each door for the reception of the offset portion 10 in the manner clearly shown in Figures 1 and 3 of the drawing. The extremity of the upper arm 8 is then disposed upwardly 95 for disposition in a plane parallel to the front 1 of the boiler and secured to the front 1 at a point directly above the meeting edges of the vertically swinging doors 2 and 3 is the flat strip of metal 13, the free 100 ends of this strip being bent to form the keepers 14 and 15 respectively with which cooperate the extremities 12 of the upper ends of the arms of the double L-shaped latches 6 and 7. In order that the extremities 12 may efficiently cooperate with the respective keepers, the inner edge portions of these extremities are slightly bent as shown very clearly in Figure 2.

Similar keepers 16 and 17 are secured on 110 the front 1 of the boiler below the doors 2 and 3 adjacent the meeting edges thereof

and the extremities 18 of the lower elongated arms 19 of the double L-shaped latches 6 and 7 cooperate with these keepers in the manner shown very clearly in Figure

5 1. Suitable guide brackets 20 are secured on the doors adjacent the lower edges thereof for the lower elongated arms 19 of the double L-shaped latches.

A handle 21 extends outwardly from the 10 intermediate horizontally disposed arm 22 of each of the double L-shaped latches to facilitate the actuation of the latch members for opening the doors in the manner to be presently described.

15 By pivotally mounting the latch members in the manner as shown and above described, the extremities of the latch members will have a tendency to normally be disposed in engagement with the respective keepers 20 whereby the doors 2 and 3 will be held in a closed position against any possibility of being accidentally opened. Whenever it becomes necessary to open the doors in order to obtain access to the fire box of the boiler, 25 the handles 21 are grasped and the latch members are swung inwardly toward each other, and this swinging movement will result in the extremities of the double L-shaped latches being brought out of engagement with their respective keepers, thus 30 permitting the doors 2 and 3 to be swung outwardly on their hinges 4 to an open position.

The provision of a closure fastener of the 35 above mentioned character will insure the positive securing of the doors when closed, and due to its simplicity, the closure fastener structure will at all times be positive and efficient in its operation and furthermore the device can be easily and read-

ily attached to a boiler without necessitating any material alterations on the parts of the boiler with which the closure fastener is to be associated.

While we have shown the preferred embodiment of our invention it is to be understood that minor changes may be made in the invention without departing from the spirit of the same or scope of the appended claims.

Having thus described the invention, what we claim as new is:—

1. In a closure fastener for the vertically swinging closure of a boiler, a double L-shaped latch pivoted adjacent its upper end on the closure, a pair of oppositely disposed keepers secured on the boiler above and below the closure, the weight of the lower end of the latch tending to normally hold the extremities of the double L-shaped latch 60 in engagement with the respective keepers.

2. In a closure fastener for the swinging doors of a boiler which are hinged at their outer ends on the front of the boiler, a pair of double L-shaped latches pivoted adjacent their upper ends on the outer faces of the respective swinging doors adjacent the free edges thereof, the ends of the double L-shaped latches extending beyond the upper and lower edges of the doors, and keepers secured on the front of the boiler above and below the doors, the weight of the lower ends of the double L-shaped latches tending to normally hold the extremities of said latches in engagement with the respective 75 keepers.

In testimony whereof we affix our signatures.

CHARLES E. JONES.
DONALD A. WHOOLERY.
